CLAIM

The ornamental design for a display screen with animated graphical user interface, as shown and described.

DESCRIPTION

FIG. 1 is a front view of an electronic device with display screen with animated graphical user interface showing a first image in a sequence according to a first embodiment of the claimed design;

FIG. 2 is a front view thereof showing a second image in the sequence of the first embodiment;

FIG. 3 is a front view thereof showing a third image in the sequence of the first embodiment;

FIG. 4 is a front view thereof showing a fourth image in the sequence of the first embodiment;

FIG. 5 is a front view of an electronic device with display screen with animated graphical user interface showing a first image in a sequence according to a second embodiment of the claimed design;

FIG. 6 is a front view thereof showing a second image in the sequence of the second embodiment;

FIG. 7 is a front view thereof showing a third image in the sequence of the second embodiment; and,

FIG. 8 is a front view thereof showing a fourth image in the sequence of the second embodiment.

The appearance of the transitional image sequentially transitions between the images shown in FIGS. 1-4 or FIGS. 5-8, respectively.

The process or period in which one image transitions to another image forms no part of the claimed design. The sharp-cornered dashed broken-line rectangle shows the perimeter of a display screen. The dashed broken lines outside this perimeter show portions of an electronic device. The dashed broken lines within the perimeter show features

(Continued)

of a graphical user interface. The dashed broken lines form no part of the claimed design. The dash-dot lines form part of the claimed design.
